UNITED STATES PATENT OFFICE.

JULIUS BUEB, OF DESSAU, GERMANY.

MANUFACTURE OF GAS.

1,181,431.

Specification of Letters Patent.

Patented May 2, 1916.

Application filed August 29, 1913. Serial No. 787,300.

To all whom it may concern:

Be it known that I, JULIUS BUEB, a subject of the Emperor of Germany, and a resident of Dessau, Germany, have invented a certain new and useful Improvement in the Manufacture of Gas, of which the following is a specification.

This invention relates to certain improvements in the art of making gas and it refers particularly to an improved method of distilling coal in a vertical retort oven for the production of gas.

In my United States Patent No. 904,043 as well as in a pending application filed by me under Serial No. 776,324, on June 28th, 1913, I have described a method of making gas by the distillation of coal in a vertical retort oven, whereby great advantages in the ~~form~~ of superior gas as well as of tar were obtained.

In the present invention I describe certain details which play an important part in obtaining a considerably higher efficiency of the gas making process, the said details referring chiefly to the loss of gases, under certain conditions.

In the practice of my methods of running the distillation of coal in the vertical retorts described in U. S. Patent No. 904,043 and application for U. S. Letters Patent filed on June 18th, 1913, under Serial No. 776,324, I have observed that the pressure within the gas retort varies greatly according to the origin of the coal and that it sometimes rises so high that immediate measures have to be taken to reduce the pressure of the gas, as the latter escapes through the otherwise sufficiently tight closures at the lower end of the retort. This escaping gas of course reduces the yield and is also a great annoyance, and I have finally succeeded in avoiding this after having tried various means.

For the better understanding of my invention I give the following details: In distilling coal of various origins according to my method described in the above patent and application, I have observed that, within the retort, considerable pressure is created in the first period while the distilling off of the volatile matter is going on. Undoubtedly this phenomenon has its cause in an unusually greater development of volatile gases and tar; the pressure rises in about two hours after the beginning of the distillation to more than 400 mm. Owing to the

high pressure it is quite natural that gas escapes through the closures at the lower end of the vertical retort, causing losses and great annoyance. I have now made the observation that this unpleasant occurrence may be avoided if one admits steam from below into the retorts as soon as the gas pressure exceeds the usual height and it is rather surprising to see that the pressure is immediately reduced to its normal height and that the escape of smoke is stopped.

The drawing is a vertical longitudinal section of a vertical retort, parts being broken away, similar to those shown and described in my Patent No. 904,043 as well as in my copending application Serial No. 776,324, certain parts being modified as hereinafter set forth.

In the drawing *a* indicates the retort made of any suitable material as set forth in my prior patent and application referred to. The space of gasification formed in each retort is provided at the top with a gas discharge *b* and a turnable cover *c* and at the bottom with a horizontal shutter *d* or similar device.

e is an annular ring fastened to the bottom of retort *a* by means of flange *f* and carrying shutter *d* on flange *g*.

h is a conveniently shaped filling piece of fireproof material or the like, so as to keep the lowermost layer of coal on a level with the top surface of the bottom of the retort and thereby to insure a complete gasification of the coal.

i, i indicate upwardly opening channels in filling piece *h* and *j* indicates a steam pipe adapted to discharge through the wall of ring *e* into the channels *i, i* of filling piece *h*.

It will be observed that, in order to practice my invention as set forth, I introduce steam as already pointed out above, during the very first stage of the coking process and only for a short time through pipe *j* into the bottom of the retort a short distance from its lower closure, thus enabling me to avoid the existence of a pressure higher than the usual one within the retort.

I am well aware that in the prior art steam has been introduced into the coking retorts to obtain so-called water gas as an additional product. But I may say here that in the prior art the steam has always been admitted in the final stage of the distillation process only, when the retort and its contents were at the highest temperature.

The purpose of the introduction of steam has always been to take advantage of the great heat in order to effect a chemical reaction between the highly incandescent coke and the water, resulting in the generation of hydrogen and carbon monoxide gas which are valuable constituents of gas for industrial as well as for domestic purposes. But the difference between my invention and 10 the introduction of steam for the generation of hydrogen and carbon monoxide is great and important. In the latter manipulation the steam is added in the final stage of the coking process when a certain pressure is 15 prevailing, and this pressure naturally rises as soon as the chemical reaction between the incandescent coke and steam takes place owing to the high temperature of the coke.

In the present invention the conditions 20 are greatly different, for at the time I introduce the steam into the retort the coal is in the primary stage of coking and its condition as to temperature etc., is far away from that permitting the generation of water gas. A further principal difference lies in the fact that in the present invention an enormously high pressure already exists and the introduction of steam into the retort

serves to allay the pressure and to reduce it to its normal height.

What I claim is:

1. In the distillation of coal rich in volatile matter, the method of avoiding loss of gas in the primary stage of the distillation consisting in reducing the high pressure to 35 the normal degree by introducing steam into the retort in said primary stage for a short time only under conditions preventing an increase of gas volume from decomposition of the steam.

2. In the distillation of coal rich in volatile matter, the method of avoiding loss of gas in the primary stage of the distillation consisting in reducing the high pressure to 45 the normal degree by introducing steam into the lower part of the retort in said primary stage for a short time only under conditions preventing an increase of gas volume from decomposition of the steam.

In testimony whereof I have signed this 50 specification in the presence of two subscribing witnesses.

JULIUS BUEB.
